H. M. THOMAS,
SUPPORTING PIN AND CUTTER.
APPLICATION FILED JAN. 3, 1921.

Patented Apr. 18, 1922.

2 SHEETS—SHEET 2.

UNITED STATES PATENT OFFICE.

HOCKLEY M. THOMAS, OF NEW YORK, N. Y.

SUPPORTING PIN AND CUTTER.

1,413,435.

Specification of Letters Patent. Patented Apr. 18, 1922.

Application filed January 3, 1921. Serial No. 434,658.

To all whom it may concern:

Be it known that I, HOCKLEY M. THOMAS, a citizen of the United States, and resident of the city of New York, borough of Manhattan, county of New York, and State of New York, have invented a new and Improved Supporting Pin and Cutter, of which the following is a full, clear, and exact description.

10 My invention relates to a supporting pin and cutter, and aims to provide certain improvements over my prior application Serial #422,250 filed November 6, 1920.

15 In connection with my prior device which relates to an article permitting of a roll of material, such as linoleum, being retained in a vertical position, and manipulated while in this position to measure and cut the same, it has been found that it would be to advantage to provide a slightly improved form 20 of pin, together with an improved type of cutting mechanism to permit of the more ready manipulation of the roll of material, as well as enhancing the appearance of the 25 same.

With this in view, I have provided a device of the nature specified, which shall be of a more particular commercial design, as well as present a better appearance than the 30 pin afore referred to.

A further object of my invention is the provision of certain cutting mechanism, associated with the pin, so that this part of the operation may be more readily accomplished.

A still further object of my invention is the provision of a pin embodying exactly the same idea as is incorporated in the prior application referred to, but which shall be 40 capable of being manipulated in an easy manner, so that it may readily be associated with and detached from the roll of material to which it is applied.

Further objects of my invention will appear in the annexed specification and drawings, which latter present practical embodiments of my invention, and in which—

Figure 1 is a perspective view of a supporting pin constructed in accordance with 50 my invention, applied to a roll of material to be cut.

Figure 2 is a fragmentary enlarged side view of the head of the pin associated with the cutter.

Figure 3 is a sectional side view of these 55 parts.

Figure 4 is a sectional plan view taken along the lines 4—4 of Figure 3 in the direction of the arrows.

Figure 5 is a fragmentary view of the face 60 of the pin.

Figure 6 illustrates a slightly different form of pin which may be utilized to advantage.

Figure 7 is an enlarged sectional plan 65 view taken along the lines 7—7 in the direction of the arrows in Figure 6, and

Figure 8 is a partly fragmentary side view of still another form of pin.

In these views the reference numeral 10 70 indicates the roll of material to be cut, which is supported in a vertical plane above the surface 11.

Referring now more particularly to my improved pin, it will be seen that the same 75 comprises a tube 12 of any desirable material, but preferably metal, which is provided with a longitudinal slot 13 extending from a point adjacent the upper end of the tube, through the lower edge of the same. 80

In this connection, it is to be noted that the length of the slot 13 is preferably slightly shorter than the width of the material 10, and with a view of providing means permitting of the material being 85 firmly held with respect to the pin, and the latter with respect to the supporting surface, it is to be noted that the upper edge of the slot 13 presents knife edges 14. Thus upon the material having been threaded through 90 the slot 13 a pressure or impact upon the head 15 will serve to drive the knife edges 14 into the upper edge of the material 10, and the spikes or gripping elements 16 associated with the lower end of the tube into 95 the supporting surface 11. Thus it will be seen that the tube will firmly engage the supporting surface and that the material 10 will be retained in applied position by virtue 100 of its frictional engagement with the supporting surface, in addition to the engagement provided by the knife edges 14, so that any accidental movement of the parts subsequent to this manipulation of the pin will be effected.

Now with a view of providing the suitable cutter, it will be noted that I utilize a collar 17, which slidably encircles the tube 12,

and is normally retained at the upper end thereof by any suitable means such as a bayonet slot and pin provision 18.

A finger piece 19 is secured to the collar 17 so that upon a disengagement on the part of the elements 18 being effected, pressure may be brought to bear upon the collar to cause the same to move longitudinally of the tube 12.

- 10 A pair of preferably rotary cutters 20 are removably attached as at 21 to the collar 17, and it will be obvious that upon a manipulation of this collar along the body of the pin that these cutters will serve to completely and easily sever the material 10 in a line slightly to one side of the slot 13, adjacent to which they lie, it being noted that the collar 17 is provided with a split portion 22, preventing engagement between the same and the material adjacent the second slot. Also although obviously any suitable type of cutter may be employed to advantage, it is to be noted that I preferably utilize as aforesaid, rotary cutters 20, 25 which are removable for the purpose of replacement, sharpening, etc., and which have, as has been illustrated in Figure 4, their flat faces lying flush against each other.
- 30 From the foregoing it will be appreciated that I have constructed a supporting pin and cutter, which will primarily present improved construction over my prior application, in that a convenient type of cutter is 35 associated with the pin, the material is properly held, and that the pin as a whole, presents a more compact and pleasing appearance, aside from the fact that the severed material will readily clear the collar 17, 40 incident to the ridge 23 or other element lying in line with the cutters 20, employed for this purpose.

It will be obvious that in some instances, difficulty might be experienced incident to 45 the application of the pin to the roll of material to be cut, when the latter is in a vertical position for the limitations incident to height of the ceiling, etc., and with this in view, I may conveniently construct the 50 pin, as has been illustrated in Figure 6, in which it will be seen that the identical construction employed in Figures 1 to 5 is resorted to with the exception that one of the legs 24 of the tube is of a length equal 55 to the tube 12, but that the second leg 25 thereof, terminates at a point beyond the cutting edges 14. Thus the pin is capable of being hooked over the edge of a roll of material, while the same is in a vertical plane 60 without the necessity of having any great amount of clearance between the ceiling and the upper edge of the roll of material.

It will be obvious in this form that difficulty might be experienced incident to the 65 downward pressure exerted by the cutter

upon the collar clearing the lower end of the leg 25 for the reason that no side support would be furnished to the roll of material (not shown) and with this in view, the slot 26 may preferably be slightly wider than the slot 13 and the collar 27 may have, in lieu of its edges terminating adjacent the split portion, as has been indicated by the reference numeral 22 in Figure 4, its edges extending inwardly as has been indicated 75 by the reference numeral 28, whereby to provide bearing surfaces engaging both faces of the material 10, as in Figure 7, and acting as a guide for preventing any displacement on the part of the same, and insuring a cut parallel to the leg 24.

If on the other hand, it is desired to derive the support advantages presented by the structure illustrated in Figures 1 to 5, and at the same time to present, as a part 85 of the pin structure permitting of its more ready manipulation as in Figure 7, the structure shown in Figure 8 may be adapted.

In this view, similar to Figure 6, the pin 90 includes a longer and shorter leg 24 and 25, but the section 29 removed from the leg 25 is hingedly secured thereto as at 30. By means of this construction it will be possible to elevate the section 29 to the position 95 indicated in dotted lines, so that the pin may be placed in applied position with a minimum of manipulation, subsequent to which the section 29 may be permitted to fall to a point at which it will lie parallel 100 to the leg 24, thus presenting to all outward appearances, the structure illustrated in Figure 1, and it will be obvious that it will also operate in the manner described in connection with the structure referred to. 105

From the foregoing it will be appreciated that in all of the forms illustrated, I have provided a supporting pin which will firmly hold the material to be cut against movement with respect to the pin, or to the supporting surface upon which the same rests, and by means of which a straight cut may be effected involving the expenditure of but a minimum of energy, as well as eliminating wastage, incident to making a diagonal cut, 115 which is now often the case.

Also my pin may be subjected to numerous changes lending themselves ideally to the association in which the pin is to be embodied. Further numerous refinements may be resorted to without in the least departing from the scope of my claims, which are—

1. A supporting pin, including a body portion presenting a slot extending from 125 a point adjacent one of its ends through to the opposite end thereof, and adapted to receive material to be cut, said slot being of a shorter length than the width of the material to be cut. 130

2. A supporting pin, including a body portion presenting a slot extending from a point adjacent one of its ends through to the opposite end thereof, and adapted to receive material to be cut, said slot being of a shorter length than the width of the material to be cut, and means at the opposite end of said slot for effecting a cutting action.
- 10 3. A supporting pin, including a body portion presenting a slot extending from a point adjacent one of its ends through to the opposite end thereof, and adapted to receive material to be cut, said slot being of a shorter length than the width of the material to be cut, the opposite end of said slot presenting a cutting edge.
- 15 4. A supporting pin, including a body portion presenting a slot extending from a point adjacent one of its ends through to the opposite end thereof, and adapted to receive material to be cut, said slot being of a shorter length than the width of the material to be cut, the opposite end of said
- slot presenting a cutting edge, and a head 25 secured to said body portion and at a point beyond said cutting edge.
5. A supporting pin, including a body portion formed with a slot extending from a point adjacent one of its ends, through 30 to the opposite thereof, a collar slidably engaging said pin, a cutter secured to said collar, said pin being adapted to engage material to be cut, and means associated with said collar and in line with said cutter for 35 displacing the material laterally, subsequent to its severance by the cutter.
6. A supporting pin, including a body portion presenting a pair of spaced legs, cutting means slidably mounted upon said 40 body portion, one of said legs terminating at a point short of the point of termination of the second of the same, and a member providing an extension for said shorter leg, and hingedly attached to the end of the 45 same.

HOCKLEY M. THOMAS.
